US00D903297S

(12) **United States Design Patent** (10) Patent No.: **US D903,297 S**
(45) Date of Patent: **** Dec. 1, 2020**

(54) **SPORT HAND-HELD FAN**

(71) Applicant: **Irvin Marlowe Deener, Jr.**, Sterling, VA (US)

(72) Inventor: **Irvin Marlowe Deener, Jr.**, Sterling, VA (US)

(73) Assignee: **Irvin Marlowe Deener, Jr.**, Sterling, VA (US)

(**) Term: **15 Years**

(21) Appl. No.: **29/699,729**

(22) Filed: **Jul. 29, 2019**

Related U.S. Application Data

(63) Continuation-in-part of application No. 29/669,380, filed on Nov. 7, 2018, now Pat. No. Des. 896,499, and a continuation-in-part of application No. 29/669,381, filed on Nov. 7, 2018, which is a continuation-in-part of application No. 29/669,380, filed on Nov. 7, 2018, now Pat. No. Des. 896,499.

(57) **CLAIM**

The ornamental design for a sport hand-held fan, as shown and described.

DESCRIPTION

FIG. 1 is a front-top perspective view of a sport hand-held fan showing my new design;

FIG. 2 is a front-bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines depict portions of the article that form no part of the claimed design.

1 Claim, 8 Drawing Sheets
